ALBERT H. DE VOE, OF WESTFIELD, NEW JERSEY, ASSIGNOR TO THE SINGER MANUFACTURING COMPANY, A CORPORATION OF NEW JERSEY.

PRESSER-FOOT MECHANISM FOR SEWING-MACHINES.

1,270,929.

Specification of Letters Patent.

Patented July 2, 1918.

Application filed September 2, 1915. Serial No. 48,594.

To all whom it may concern:

Be it known that I, ALBERT H. DE VOE, a citizen of the United States, residing at Westfield, in the county of Union and State 5 of New Jersey, have invented certain new and useful Improvements in Presser-Foot Mechanisms for Sewing-Machines, of which the following is a specification, reference being had therein to the accompanying drawings.

This invention has for its primary object to provide means for fully controlling the position of a sewing machine presser-foot from beneath the support of the sewing machine in order that the hands of the operator may be entirely free for the adjustment and other manipulation of the work.

In its preferred embodiment, the machine is provided with a spring-pressed presser-bar having fixed thereon a collar affording a shoulder to receive the thrust of a loose sleeve also applied thereto and actuated by a lifting rock-lever operatively connected with a treadle- or knee-lever beneath the work-table and constituting the primary presser-bar lifting means. The sleeve is provided with a lateral stud to afford a shoulder for engagement with either of two cam portions or a detaining shoulder of a 25 finger-lever preferably adapted to serve not only as a detent but as an auxiliary lifter for raising the sleeve and with it the presser-bar independently of the primary lifting lever.

The finger-lever is fulcrumed below and intermediate its extreme lateral positions and is formed with a slot embracing the lateral stud of the sleeve with one substantially straight cam-edge in tangential relation with an imaginary circle concentric with its 35 fulcrum and normally resting upon the said stud. Thus, in the rise of the sleeve under the action of the primary lifting lever, the engagement of such cam-edge therewith will cause the finger-lever under its inertia to 40 progressively assume different positions in which its center of gravity remains upon the same side of the fulcrum, or to move by momentum into a position wherein its center of gravity is upon the opposite side of the 45 fulcrum to cause said stud to enter a recess or pocket upon the opposite side of said slot affording a detaining shoulder for positive engagement with the stud. The position which the finger-lever assumes is determined 50

55 by the speed of rising movement of the

sleeve, a comparatively slow movement of the latter insuring the continued contact of the stud with the cam-edge of the slot so that the release of the sleeve by the primary lifting lever permits the sleeve to drop without 60 obstruction, while a more rapid rise of the sleeve under the action of the primary lifting lever causes the swinging of the finger-lever by momentum to the opposite side of its fulcrum for entrance of the stud into its 65 detaining recess or pocket. In this position of the finger-lever, the sleeve, and hence the presser-bar, is locked in its upper or work-releasing position.

The detaining pocket of the finger-lever is 70 flared so as to produce an outwardly inclined outer edge, and the slight lift of the sleeve beyond normal raised position serves by engagement of its stud with said inclined edge to throw the lever into opposite extreme 75 or releasing position with its tangential cam edge in contact with the lateral stud of the sleeve, whereby release of the primary lifting lever permits the sleeve to freely descend and the presser-bar to fall for engagement of the presser-foot with the work.

It is thus evident that the quickness with which the primary lifting lever is actuated determines whether the detaining finger-lever shall assume releasing or detaining position, and hence whether the presser-foot shall promptly descend upon the work upon the release of the primary lifting lever or whether it shall remain elevated for a subsequent actuation of the primary lifting lever 85 for unlocking the presser-bar from raised position.

The invention will be understood by reference to the accompanying drawings, in which Figure 1 is a rear side elevation of a 90 Singer No. 62 double-chain-stitch machine provided with the present improvement, and Fig. 2 a front end view of the same with the face-plate removed. Fig. 3 is a view of the presser-bar lifting device similar to Fig. 2 95 but with the finger-lever represented in different full and dotted line positions. Fig. 4 is a perspective view of the detaining finger-lever and its fulcrum-pin.

As represented in the drawings, the machine frame comprises the base 1 from which rises the hollow standard 2 sustaining the tubular overhanging arm 3 terminating in the head 4, the base having secured thereon the work-plate 5. Within the head are jour- 105

naled the reciprocating needle-bar 6 carrying the needles 7 and the forward and rearward presser-bars 8 and 9 normally pressed downwardly by means of the springs 10 and 5 11 and having secured upon their lower ends the forward and rearward presser-feet 12 and 13 opposed to the work-plate 5 and the feed-dog 14.

The presser-bar 9 has fixed thereon by 10 means of the set-screw 15 the collar 16 formed with a forked lateral extension embracing the bar 8, and has applied thereto beneath said collar the loose sleeve 17 provided at the lower end with a lateral ex- 15 tension 18 projecting beneath and adapted to engage the under face of the collar 19 fixed upon the presser-bar 8 by means of the set-screw 20. The sleeve 17 is formed with a rearwardly projecting boss 21 provided 20 with the pin 22 which enters an elongated aperture 23 at the forward end of the primary presser-foot lifting rock-lever 24 which is fulcrumed intermediate its ends upon the stud-screw 25 tapped into the rear- 25 ward side of the tubular arm 3. The lever 24 has in its rearward arm an aperture 26 entered by the hooked upper end of the rod 27 passing through the work-plate 5 and having fixed thereon the collar 28 formed 30 with an apertured lateral lug 29 to which is attached the upper end of the treadle- or knee-lever rod 30 by means of which the lever 24 is rocked in a manner well known to lift the sleeve 17 and with it the presser bars 8 and 9 and the presser-feet carried 35 thereby.

Fixed within the lower portion of the bracket-arm head 4 is the fulcrum-pin 31 upon which is mounted the enlarged lower 40 or hub portion 32 of the finger-lever 33 which is provided above the fulcrum-pin with the slot 34 having in the side adjacent the body portion of the lever the substantially straight cam-edge 35 in tangential 45 relation with an imaginary circle concentric with the fulcrum-pin 31, and having in the outer portion of its opposite edge the lateral flaring recess or pocket 36 formed with the detent shoulder 37 and the up- 50 wardly and outwardly inclined cam edge 38. The sliding sleeve 17 carries a roller-stud 55 39 which enters the slot 34 and is adapted to engage, when required, the cam edges 35 and 38 and the detent-shoulder 37 of the finger-lever.

When the presser-feet 12 and 13 are depressed for a stitching operation, as represented in Figs. 1 and 2, the sleeve 17 is confined in its lower position by the collars 16 and 19, and the stud 39 is in the lower or inner portion of the slot 34 of the detaining finger-lever. In case the operator desires to temporarily lift the presser-feet for adjustment of the work, the lifting lever 24 60 is tilted by a comparatively slow movement

of the operating treadle or knee-lever, and the rise of the sleeve 17 carries the stud 39 upward in continuous contact with the cam-edge 35, the body of the lever 33 swinging upwardly but remaining upon the same side 70 of a vertical line passing through the fulcrum-pin 31, as represented in dotted lines in Fig. 3. In case the operator desires the presser-feet to remain in raised position after release of the lifting lever 24, a quick 75 movement of the latter causes the stud 39 to swing the lever 33 with sufficient speed to cause its momentum to carry it into its opposite extreme position at the opposite side of the fulcrum-pin 31, whereby it is 80 caused to assume the locking position represented in full lines in Fig. 3, with the stud 39 resting upon the detaining shoulder 37. The release of the lever 24 under such condition leaves the presser-feet locked in their 85 raised positions. In order to lower the presser-feet upon the work, a slight actuation of the lever 24 to elevate the sleeve 17 above its normal locked position causes the engagement of the stud 39 with the cam 90 edge 38 to swing the lever 33 by momentum into unlocking position whereby it is released from the pocket 36 and is caused under the action of the springs 10 and 11 to ride down the cam edge 35 while the lever 95 33 gradually assumes normal position, represented in Figs. 1 and 2.

While according to the present invention the lever 33 serves primarily as a detent for maintaining the presser-feet elevated at the will of the operator, the slot 34 has upon the side opposite the cam edge 35 a divergently inclined cam edge 40 so disposed that the operator may effect the lifting of the presser-feet by hand by shifting the lever 33 105 from the position represented in Fig. 2 to the full line position represented in Fig. 3.

In the machine represented in the drawings, two presser-bars are shown each provided with a presser-foot, but it is evident that the present improvement is equally adapted for embodiment in machines employing only a single presser-foot. It is also evident that the present improvement is not limited to the particular construction 110 and arrangement of parts herein shown and described, its leading feature being the provision for control of the period during which the presser-foot remains elevated by means disposed beneath the work-plate so 115 that the hands of the operator may be entirely free to manipulate the work.

Having thus set forth the nature of the invention, what I claim herein is:—

1. In a sewing machine, in combination, a 125 presser-foot, a lifter therefor, and means movable by and adapted to continue its movement independently of said lifter for detaining the presser-foot raised when desired.

2. In a sewing machine, in combination, a presser-foot, a detent-lever provided with release and detaining portions for control of the action of the presser-foot, connecting means between said lever and the presser-foot, a lifter for the presser-foot, and connections between said lifter and said detent-lever for causing movement of the detent-lever from the lifter whereby the presser-foot may be detained raised or released from a raised position when desired. 10
3. In a sewing machine, in combination, a presser-foot, a lifter therefor, and a detent for maintaining the presser-foot raised and controllable through said lifter by a single application of force to be either effective or ineffective in maintaining the presser-foot raised after it has been elevated. 15
4. In a sewing machine, in combination, a presser-foot, a lifter therefor provided with means for locking the presser-foot in raised position, and a second lifter adapted to operate the first-named lifter to render it either effective or ineffective for locking the presser-foot in raised position. 20
5. In a sewing machine, a presser-foot, a lever, a treadle connection to said lever, and means operable through said treadle connection and lever for raising and either locking in raised position or releasing said presser-foot by a single application of foot power in the same direction. 30
6. In a sewing machine, a presser-foot, two separate and distinct presser-foot lifting levers, one of which is shaped to detain the presser-foot raised, said presser-foot lifting levers being operatively connected to the presser-foot in such wise that operation of one lever to elevate the foot may be utilized to effect a detaining of the presser-foot raised by the other. 35
7. In a sewing machine, a presser-foot, lifting mechanism including a lifting lever
- operated from below the machine, and a detent shaped to hold the presser-foot raised 45 and controlled by said lever to effect a locking of the presser-foot in raised position whereby the presser-foot may be moved from work-engaging position and held elevated or lowered as desired by a single application of 50 foot power.
8. In a sewing machine, a presser-foot, treadle and hand operable lifting levers operatively connected with said presser-foot for permitting it to be moved by either hand 55 or foot power, said hand operable lifting lever being capable of manipulation by said treadle operable lifting lever to effect a locking of the presser-foot in raised position and through a momentary application of foot- 60 power.
9. In a sewing machine, a presser-foot, a lever, a treadle connection for moving said lever and thereby lifting said presser-foot, and means operatively arranged with relation to said lever and presser-foot for securing said presser-foot in raised position whereby through rapid and slow applications of foot power the presser-foot may be elevated with or without respectively a se- 70 curing thereof in raised position.
10. In a sewing machine, a presser-bar, a presser-foot carried thereby, a lever connected to said bar, a treadle connection for moving said lever and lifting said bar and 75 presser-foot, a detent operatively connected to said bar, said detent being shaped to permit the elevation of said presser-foot with or without a locking thereof in raised position and said detent being actuated through 80 its connection with the presser-bar when the bar is lifted by an application of foot-power through the treadle connection.

In testimony whereof, I have signed my name to this specification.

ALBERT H. DE VOE.
